Primary Examiner — Janice Hallmark(74) *Attorney, Agent, or Firm* — Thomas A. O'Rourke; Bodner & O'Rourke, LLP(57) **CLAIM**

The ornamental design for a toy bone, as shown and described.

DESCRIPTION

FIG. 1 is a perspective view of a toy bone illustrating my new design.

FIG. 2 is a top view of the toy bone of FIG. 1.

FIG. 3 is a front view of the toy bone of FIG. 1.

FIG. 4 is a bottom view of the toy bone of FIG. 1.

FIG. 5 is a rear view of the toy bone of FIG. 1.

FIG. 6 is a left side view of the toy bone of FIG. 1.

FIG. 7 is a right side view of the toy bone of FIG. 1.

FIG. 8 is a perspective view of a toy bone illustrating a second new design.

FIG. 9 is a top view of the toy bone of FIG. 8.

FIG. 10 is a front view of the toy bone of FIG. 8.

FIG. 11 is a bottom view of the toy bone of FIG. 8.

FIG. 12 is a rear view of the toy bone of FIG. 8.

FIG. 13 is a left side view of the toy bone of FIG. 8; and, FIG. 14 is a right side view of the toy bone of FIG. 8.
